UNITED STATES PATENT OFFICE.

CHESTER ARTHUR WYATT, OF UNION CITY, TENNESSEE.

OIL-STOVE OVEN.

1,410,982.

Specification of Letters Patent. Patented Mar. 28, 1922.

Application filed June 4, 1921. Serial No. 475,025.

To all whom it may concern:

Be it known that I, CHESTER ARTHUR WYATT, a citizen of the United States, residing at Union City, in the county of Obion and State of Tennessee, have invented certain new and useful Improvements in an Oil-Stove Oven, of which the following is a specification.

My invention relates to ovens adapted for use on oil or gas stoves, the primary object being the provision of an oven constructed in a novel manner whereby heat is not only circulated around the walls thereof, but is carried through the interior of the oven.

15 A further object is the provision of an oven in which the heat is uniformly distributed throughout.

With these, and such other objects in view as will be apparent from the description, my 20 invention resides in the novel construction, combination and arrangement of parts hereinafter described and claimed and illustrated in the drawings in which—

Figure 1, is a vertical section through the 25 oven from the front;

Figure 2, a horizontal section on line 2—2 of Figure 1;

Figure 3, a front elevation of the oven;

Figure 4, a side elevation thereof; and

30 Figure 5, a detail perspective, partly in section, illustrating the disposition of the oven, relative to the arrangement of the walls and flues.

In detail, the oven comprises a base plate, 35 or bottom, 1, adapted to be positioned on the top of an oil stove and having a central, oval-shaped aperture 2, to engage over the stove burners whereby heat is admitted to the oven.

40 The outer walls of the oven consist of a back 3, top 4, side walls 5, and a front 6, all of which are suitably connected together. A door 7 is mounted by means of hinges 8 in the front 6, and in this preferred form 45 is provided with a glass panel 9 for an obvious purpose.

As a supporting means for the door when lowered, I provide rods 10 having ball and socket connection with the door as at 11 and 50 engaging at their lower ends with angle slots 12 in the front 6. Heads 13 on the rods serve to engage the interior surface of the front 6 and support the door when in lowered position. A door latching mechanism 55 comprises the central pivot member

14 having connected therewith latch rods 15 adapted to engage keepers 16 on the interior of the front 6, as illustrated in Figure 3.

Spaced from the outer walls at the sides, 60 top and back, is an intermediate shell comprising side walls 17, a back wall 18 and top 19 suitably connected together and supported by the bottom plate 1. Side walls 17 and top 19 engage the front 6 providing 65 an air space extending over the top, down the back and around the sides of the oven. By reason of the engagement of the walls 17 with the bottom 1, the heat from the stove burners is not admitted to the space thus 70 formed except in a manner to be described.

The interior of the oven is formed of side walls 20 connected with the top 19 to provide a spaced passageway between said walls 20 and the walls 17 and 18. The bottom 75 of the chamber, or the interior of the oven, is formed of downwardly inclined sections 21 which meet at substantially the central portion of the bottom plate 1, as best illustrated in Figure 1. Tray supports 22 are 80 provided on the interior surface of the walls 20 and if desired provision may be made for the usual drip pan 23 at the bottom of the walls 20, a support for the drip pan being 85 formed by the sections 21.

Extending transversely through the interior of the oven and spaced below the top wall 19 are flues 24. In this preferred form of my invention, the flues are four in number and one pair of these flues is supported 90 on one end in the interior side wall 20 and at the opposite end in the intermediate side wall 17, whereby communication is permitted between the interior heat passageway from one side through and across the top of the 95 oven chamber and into the outer air passageway at the opposite side of the oven. The other pair of flues is arranged in a reverse manner, the separate flues being disposed in alternate relation, as best illustrated in Figure 2. The outer side walls 5 of the oven are provided with doors 25 in alignment with the flues 24, for the purpose of cleaning the same. Perforations 26 are arranged in the lower ends of the outer side walls 5 for 100 the escape of the heat and gases after they have completed their travel through them.

By this arrangement and disposition of 105 walls and flues, it will be seen that the heat from the stove burners will travel upwardly 110

through the aperture 2 in the bottom of the oven along the inclined sections 21 and up the interior passageways at each side of the oven between the inner side walls 20 and intermediate side walls 17, entering the flues 24 and passing therethrough to the outer passageway between the outer side walls 5 and intermediate the walls 17, and from this point downwardly along the back of the oven and out through the perforations 26 provided in the outer side walls 5. It will thus be seen that a uniform distribution of the heat is secured by reason of the spacing of the walls and the disposition of the alternate arrangement of the flues. All parts of the oven are made from suitable sheet metal and can be secured together in any approved form or cast in sections if desired.

While I have described and illustrated certain details and materials which enter into the construction and operation of my invention, I desire it to be understood that I do not intend to limit myself to these, but that any such may be used and any changes made in the same as will fall within the scope of the invention as claimed.

I claim:

1. In an oven of the character described, an outer shell having an apertured bottom for the admission of heat thereinto, an inner shell supported on said bottom in spaced relation from the said outer shell, an oven chamber in spaced relation from said inner shell, conduits extending through said oven chamber and communicating alternately with the outer and inner passageways between said shells, and means in said outer shell for the escape of heat and gas.

2. An oven of the character described, comprising an apertured bottom, a back, top, front and side walls mounted thereon, a shell in spaced relation within said walls and in parallel disposition therewith to provide heat passageways at the top, back and sides of said oven, an oven chamber disposed within said shell in spaced relation thereto to provide heat passageways at the bottom

and sides of said chamber, and flue connection across the top of said shell between said passageways for circulation of heat around said chamber and shell.

3. An oven of the character described, comprising an outer shell having an apertured bottom for the admission of heat thereinto, an inner shell supported on said bottom in spaced relation from said outer shell, an oven chamber supported on said bottom in spaced relation from said inner shell, conduits extending through said oven chamber at the top thereof, and entirely thereacross, certain of said conduits providing communication between the space between the side wall of said oven chamber and the inner shell at one side of the oven and the space between the inner shell and the outer shell at the opposite side of said oven, and other of said conduits providing communication between the passageways in a reverse manner.

4. In an oven of the character described, an outer shell, having an apertured bottom for the admission of heat thereinto, an inner shell supported on said bottom in spaced relation from the outer shell, at the top, sides and back of the oven, an oven chamber with in said inner shell formed of side walls supported between the front of the oven and the back of said inner shell in spaced relation from the side walls of said inner shell, flues extending across the top of the oven chamber with the ends of certain flues communicating with the outermost air passageway at one side of the oven and the innermost air passageway at the opposite side of the oven and the other of said flues communicating in a like manner in opposite arrangement, all of said flues being disposed in a substantially horizontal plane adjacent the top of the oven, and doors provided in the outer shell of said oven in alignment with the ends of said flues whereby the said flues may be readily cleaned when desired.

In testimony whereof I affix my signature.
CHESTER ARTHUR WYATT.
